(57) **CLAIM**

The ornamental design for a mobile phone, as shown and described.

DESCRIPTION

FIG. 1 is a front-top-right-side perspective view of a mobile phone according to our new design;

FIG. 2 is a rear-bottom-right-side perspective view of the mobile phone of FIG. 1;

FIG. 3 is a front view of the mobile phone of FIG. 1;

FIG. 4 is a rear view of the mobile phone of FIG. 1;

FIG. 5 is a right-side view of the mobile phone of FIG. 1;

FIG. 6 is a left-side view of the mobile phone of FIG. 1;

FIG. 7 is a top view of the mobile phone of FIG. 1, and,

FIG. 8 is a bottom view of the mobile phone of FIG. 1.

The broken lines in the drawings show portions of the mobile phone that form no part of the claimed design.

1 Claim, 8 Drawing Sheets
